RADIO DIRECTION FINDER

Maurice A. Warren, Los Angeles, Calif., assignor to
Vec/Trak Research & Development Corporation, New
York, N.Y., a corporation of New York

Filed July 22, 1969, Ser. No. 18,323

Term of patent 14 years

Int. Cl. D14—03

U.S. Cl. D26—14

FIG. 1.

FIG. 2.

FIG. 3.

FIG. 4.

FIG. 5.

FIG. 6.

FIG. 7.

FIG. 10.

FIG. 9.

FIG. 8.

FIG. 1 is a side elevational view of a radio direction finder, showing my new design, the plug-in tuner module has been omitted for convenience of illustration;

FIG. 2 is a rear elevation thereof;

FIG. 3 is a front elevation thereof;

FIG. 4 is a side elevation as seen from the opposite side of FIG. 1;

FIG. 5 is a top plan view thereof;

FIG. 6 is a bottom plan view thereof;

FIG. 7 is a side elevation with the inclusion of the plug-in tuner module;

FIG. 8 is a rear elevation thereof;

FIG. 9 is a modified embodiment of the radio direction finder illustrated in FIG. 1; and

FIG. 10 is a rear elevation thereof.

I claim:

The ornamental design for a radio direction finder, substantially as shown and described.
